UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,826, dated March 21, 1882.

Application filed February 11, 1882. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a large flower-and-leaf group, with a central vase-like figure and a bracket-like support, all set on a stem.

B is a group set on a double stem, with an ornamental scalloped support and flowers and leaves arranged along a forked stem above.

C is a large flower-and-leaf group set on a 20 stem projecting from B, with two ornamental box-like supports, a lattice-like figure, and flowers and leaves set on stems springing from the box-like figures and traversing the surrounding parts of the design.

D is an open flower figure set on the main 25 stem from C.

E is a small flower group set on a stem from D. It consists of a scalloped supporting figure, with buds, flowers, and leaves.

F is a vase-like figure serrated below and 30 set on a stem from D, having flowers projecting from it and two stems, on one of which A is set and on a branch of the other B is set.

G is an open flower figure with projecting 35 sprays and buds, and is set on a branch of the stem from F, shown in part on one side and in part on the other side of the design.

H consists of a bracket-like figure to the

right, in the center a wreath-like figure encircling a sprig of leaves, and terminating above 40 and to the right in an open flower with petals, the whole set on a branch of the stem from F.

K consists of an open flower and leaves, and is set on a branch stem from F.

L is a bulb-like flower with projecting leaves 45 and buds, and is set on a stem from D.

M is an open flower with leaves, set on the stem from L, shown on the other side of the design.

N is a group of three open flower figures 50 with projecting buds and leaves, all arranged along a stem springing from the base of A, shown in part on one side and in part on the other side of the design.

O is a group of small flower figures arranged 55 along the stem from C and occupying the field immediately above C.

The whole effect of the design is that of a vine, branch, or stem running irregularly across a background, *a*, composed of small circular 60 figures with star-shaped centers, the vines or branches bearing upon them at intervals the various figures described.

I claim—

1. The design for carpets, consisting of the 65 figures A B C D E F G H K L M N O and connected parts, substantially as shown.

2. The design for carpets, consisting of the figures A B C D E F G H K L M N O, with connected parts, and ground *a*, substantially 70 as shown.

HENRY HUNT.
